SAW HANDLE AND MEASURING DEVICE

James N. Alexander, Birmingham, Ala.

Application January 7, 1935, Serial No. 774

Renewed September 17, 1937

3 Claims. (Cl. 33—138)

This invention relates to saws, and more particularly has reference to a handle therefor provided with a measuring device.

The advantages of a measuring device carried by a saw are believed to be obvious, when the fact is considered that the actual sawing operation is frequently dependent upon first determining the length of the desired block or piece of wood. Heretofore it has been common practice to have separate saws and measuring devices, and no means have been provided for mounting a tape measure in a saw handle in such a way that it does not interfere with the manipulation of the saw, and at the same time is ready for instant and convenient use.

One of the objects of my invention is to provide a saw handle carrying in association therewith a measuring device.

Yet another object of my invention is to provide a handle for a saw in which a tape measure is arranged and available for quick use.

With these and other objects in view which may be incident to my improvements, the invention consists in the parts and combinations to be hereinafter set forth and claimed, with the understanding that the several necessary elements comprising my invention may be varied in construction, proportions and arrangements, without departing from the spirit and scope of the appended claims.

In the accompanying drawing I have shown the application of my inventive concept to both a single-handle saw and a double-handle saw. While I have shown various modifications of my invention, it will of course be obvious that further variations may be made without exceeding the scope of the appended claims.

In this drawing, in which corresponding numerals refer to the same parts:

Figure 1 is a side elevation of a handle of a saw equipped with my invention, and a portion of the blade, the saw in this instance being a single-handle saw.

Figure 2 is a view taken along the line 2—2 of Figure 1, looking in the direction of the arrows.

Figure 3 is a sectional view along the line 3—3 of Figure 2, looking in the direction of the arrows.

Figure 4 is a sectional view along the line 4—4 of Figure 1, looking in the direction of the arrows.

Figure 5 is a view of a modified form of the device shown in Figures 1 through 4.

In Figure 1 there is disclosed a saw blade 1 of conventional construction, provided with a han-

dle 2, suitably secured thereto by means of wing nuts 3. The handle 2 is provided with a lubricant reservoir and means for feeding the lubricant to the saw blade, constructed generally along the lines set forth in my related Patent Number 2,070,105 issued February 9, 1937. The handle may be formed of any suitable material, but I have found a light-weight metal or alloy to be preferable.

The handle 2 is provided with a hand engaging portion 4, in which is formed a lubricant reservoir 5. It will be noted that the reservoir 5 is disposed in the lower portion of the hand engaging member 4, so that a tape, to be described hereafter, may be located above such reservoir.

Two ducts 6 and 7 extend forwardly from the lower portion of the reservoir to points in the face of the handle and on opposite sides of the blade 1. As best shown in Figure 4, the forward end of each duct is shouldered and internally threaded to receive a cylindrical fitting member 8 provided with an end closure 9. The closure 9 is provided with an aperture 11 which is set off from the center, and which is of restricted cross section. A cap 12 may be threaded upon the fitting 8, and provided with a centrally disposed aperture 13.

It will therefore be seen that when the cap 12 is screwed tight against the closure member 9, the duct 6, or 7, is closed, and no oil may pass therethrough. However, when the cap 12 is slightly unscrewed, as shown in the lower part of Figure 4, oil from the reservoir 5 may pass through ducts 6 or 7, through fitting 8, and thence through the apertures 11 and 13 onto the blade or the saw. It will be noted that the oil may flow by gravity, and in practice it is desirable to incline the blade to the vertical about both its horizontal and longitudinal axes, so that the oil will flow onto the top side of the blade. At the same time, the opposite cap 12 should be closed, so that no oil from its duct will drip onto the ground. The blade may then be reversed so that the opposite side is lubricated.

To accommodate a tape measure, the upper portion of the handle, or more specifically the hand engaging portion 4, may be cut away as indicated in Figure 3 to form a recess 14.

An arm 15 may be pivoted, as at 16, in the upper portion of the recess, the exterior face of the arm 15 conforming to the general contour of the saw. The arm 15 may be notched as at 60 for engagement by a spring 61 to lock the arm in closed position. Another notch 62 may be made to facilitate opening of the arm by the operator.

Securely fastened to the under side of arm 15 is a casing 17 for a conventional tape measure.

The tape 18 extends through a slot in the casing and a slot 19 in the arm 15. A suitable tab 20 is secured to the free end of the tape, which not only facilitates grasping by the operator but likewise prevents complete retraction of the tape through slot 19 and the slotted casing. As best indicated in Figure 2, the tape 18 has one end secured to a rotatable drum 10, and is wound thereabout. The drum in turn rotates on bearing 21, and resiliently resists rotation, when the tape is extended, by virtue of helical spring 22. One end of the helical spring is secured to the drum 19, while the opposite end is secured to the bearing 21.

The drum 10 is provided with detents 23, which are engaged by a pawl 24. The pawl 24 is operated by button 25, which is depressed against the tension of the spring 26 to disengage the pawl 24 from the detents 23, to thereby permit the helical spring 22 to rewind the tape upon the drum.

It will be noted from Figure 2 that the button 25 extends through the saw handle and into a cup-shaped recess 27 formed in the handle. The button 25 therefore maintains the arm 15 and tape within the handle of the saw, and yet when it is desired to pivot the arm 15 the button 25 has sufficient play so that it can be depressed to permit the tape to be swung free of the recess 14.

It will be noted that an aperture 28 extends from the reservoir 5 to the recessed portion 14. Through this aperture, lubricant may be fed into the reservoir when the tape is removed from recess 14. Although independent closure means may be employed for the aperture 28, I prefer to form integrally upon the casing 17 a closure member 29 which automatically and effectively closes the aperture 28. It will also be appreciated that the contents of the reservoir may be emptied by pivoting the arm 15 so that the tape is swung free of the recess 14.

In Figure 5 I have shown an alternative form of filling and discharge channel. In this case a channel 31 is located at the base of the reservoir 5, and a suitable screw cap 32 is provided as a closure member therefor. The tape and casing 17 are located in the top of the handle, as in Figure 3, but obviously the casing may be permanently secured within the handle if so desired.

It will of course be appreciated that there are various other modifications that can be made in the specific arrangement of the tape in the handle, and the above are exemplary merely.

The advantages of my invention are believed

to be obvious from the foregoing. In the first place a compact arrangement is afforded which at the same time affords an adequate operation of the several elements. The device is inexpensive to manufacture and is yet sturdy in construction. A carpenter is enabled to have both a saw and a tape measure in a single unit with the advantages such a construction affords.

While I have shown and described the preferred embodiment of my invention, I wish it to be understood that I do not confine myself to the precise details of construction herein set forth by way of illustration, as it is apparent that many changes and variations may be made therein, by those skilled in the art, without departing from the spirit of the invention, or exceeding the scope of the appended claims.

I claim:

1. A saw handle provided with a recess therein, a casing having a tape measure adapted to rest in the recess, a tape measure in the casing, a pivoted closure means provided with an aperture through which the end of the tape measure protrudes, a spring detent to hold the pivoted closure means in closed position, a locking device carried by the casing for the tape adapted to extend through the side wall of the recess in which the casing for the tape is housed, means to normally urge the locking device outwardly of said handle whereby the device may be released by pressure from the outside of the handle, when it is desired to remove the casing from the handle.

2. In a saw handle with a recess therein, a casing for a tape measure adapted to rest in the recess, a tape measure in the casing, a hinged lid adapted to engage and hold the casing in place, said lid conforming in shape to the surface of the casing adjacent the lid and conforming in shape to the outer contour of the saw handle at the edges of the aperture, said lid also provided with an aperture through which the said tape protrudes whereby said tape may be grasped and withdrawn by the user.

3. A saw handle having a grip portion, a saw blade, means for attaching the saw blade to the saw handle, there being a recess within said grip portion, a casing for a tape measure fitting in the recess, a tape measure in the casing, a lid adapted to hold the casing in place, hinging means pivotally joining the lid to said grip portion on the side of said lid nearest the blade, said lid having an inclined aperture allowing the end of the tape measure to protrude, said aperture being inclined upward and away from the saw blade.

JAMES N. ALEXANDER. 55
